UNITED STATES PATENT OFFICE

107,845

DESIGN FOR A TEXTILE FABRIC

Walter Ross, New York, N. Y.

Application December 11, 1937, Serial No. 73,526

Term of patent 3½ years

To all whom it may concern:

Be it known that I, Walter Ross, a citizen of the United States of America, residing in the city of New York, county of New York, and State of New York, have invented a new, original, and ornamental Design for a Textile Fabric, of which the following is a specification, reference being had to the accompanying drawing, forming part thereof.

The figure on the drawing is a plan view of a textile fabric showing my new design.

The design unit is contained between the dot-dash lines, which unit is repeated in regular succession as indicated by the extensions beyond the unit boundaries.

I claim:

The ornamental design for a textile fabric substantially as shown and described.

WALTER ROSS.
